Primary Examiner — Dana K Weiland*Assistant Examiner* — Emily Anna Saunders(74) Attorney, Agent, or Firm — Rumit Ranjit Kanakia(57) CLAIM

The ornamental design for a toy xylophone, as shown and described.

DESCRIPTION

FIG. 1 is a first perspective view of a toy xylophone showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is a perspective view of FIG. 1 in an environment of use.

The broken lines in FIG. 9 show environmental subject matter only and form no part of the claimed design. All other broken lines show portions of the toy xylophone that form no part of the claimed design.

1 Claim, 9 Drawing Sheets(56)
